CLAIM

The ornamental design for a detector cartridge, as shown and described.

DESCRIPTION

FIG. 1 is a top perspective view of a detector cartridge showing our new design.

FIG. 2 is a bottom perspective view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and,

FIG. 8 is a right side elevational view thereof.

Stippling and tangency lines shown in the drawings represent the three-dimensional contours of the design, and are not intended to indicate surface decoration. The broken lines show portions of the detector cartridge that form no part of the claimed design.
